UNITED STATES PATENT OFFICE.

JOHN P. FERRITER, OF OCEANPORT, AND WRIGHT H. JOHNSON, OF RED BANK, NEW JERSEY.

METHOD OF TELEGRAPHING BY THE USE OF ALTERNATING CURRENT.

Application filed August 29, 1923. Serial No. 660,025.

To all whom it may concern:

Be it known that we, JOHN P. FERRITER and WRIGHT H. JOHNSON, citizens of the United States, residing, respectively, at 5 Oceanport and Red Bank, in the county of Monmouth and State of New Jersey, have invented certain new and useful Improvements in Methods of Telegraphing by the Use of Alternating Current, of which the 10 following is a specification.

This invention relates to alternating current telegraph systems and has for one of its objects the adaptation to duplex working.

15 It is well known for example that high frequency carrier wave currents have been employed for signalling. Moreover that several signalling currents of different frequencies have been simultaneously transmitted and received by means of wave filters. However, great difficulty has been experienced by virtue of the frequencies being of high degree introducing strong attenuation effects. Since the frequencies employed by the present system are very low, 20 ordinary telegraph lines are made suitable for this type of transmission and especially in connection with vacuum tube repeater systems, since it is known that mechanical repeaters are much less efficient than those of the vacuum tube type.

By means of the present invention which 25 as one of its principal features involves the use of thoroughly synchronized and properly modulated half-wave modifiers, it is possible to operate printers over submarine cables when due to attenuation signals would be impossible by ordinary known means. Moreover, the signals suffer a minimum of distortion as only the amplitudes 30 of the sinusoidal half-waves are gradually affected without distorting the final sinusoidal shape of the waves.

In order to more clearly grasp the scope 45 of this invention the following figures are made part of the specifications and

Fig. 1 is a diagrammatic representation of the unmodified alternating current wave on one hand, and the amplified half wave 50 intensities for signalling the letters A, U, and E by way of example.

Fig. 2 schematically represents the synchronized transmitter means employed.

It will be seen by referring to Figure 1, 55 that in order to make the system completely

effective, it is necessary to start intensifying a selected half cycle at its beginning or at the zero point, and to complete the intensification at the end of the half cycle. To accomplish this end it is requisite that 60 synchronism be maintained between the alternating current and the transmitted signals. Our method of maintaining this synchronism is as follows.

We connect a small alternating current generator thru gears to the shaft of the printer distributor in such a manner that the distributor drives the alternating current generator directly. This alternating current generator is caused to furnish current to the telegraph line continuously and, as the generator is driven by the distributor, which transmits the telegraph signals, they are automatically kept in phase regardless of any variation in the speed of the distributor. 75

Our method of varying the intensity of the half cycles is as follows. We modify the telegraph duplex on which the printer system operates so that, instead of transmitting marking and spacing signals by alternating the polarity of the applied E. M. F., it transmits marking signals by applying the total E. M. F. of the generator to the line and transmits spacing signals by applying a reduced E. M. F. to the line. 80 This is accomplished as shown in Figure 2.

In Figure 2, (D) is the distributor on which five transmitting segments are shown. The brush arm, which is rotating continuously, is connected directly to the line and the artificial line at the mid-point of the primary winding of a one to one transformer (T). Each transmitting segment on the distributor is connected to a separate automatic tape transmitter, one of which is represented by (K). The position of the armature of (K) determines the value of the E. M. F. applied to the line and, as the distributor brush passes over the segment 90 to which (K) is connected, this E. M. F. will cause current to flow. It will be remembered that the generator (G) which is geared to (D) and rotating in synchronism with it is generating alternating current at 95 all times and that, when the distributor brush first touches any transmitting segment, the alternating current is at the zero point and, as the brush passes over the segment, the current gradually increases until 105 110

the brush reaches the middle of the segment and thereafter the current decreases until it reaches the zero point again just as the brush leaves the segment. This operation 5 is repeated on the following segment with the difference that the current increases on the opposite half of the cycle. It will be seen that when (K) is closed at (C), the current will pass from generator (G) thru 10 resistance (B), contact (C), segment (S), brush arm (BR) when it reaches segment (S), thru point (X), and to the midpoint of transformer (T) where it divides between the line and the artificial line as is 15 usual in duplexes. In following this path, the current passed thru a resistance of 100 ohms before reaching point (X). During this time, a maximum E. M. F. was applied to the line at point (X) and a marking 20 signal was transmitted. With the key closed at (O), the current would flow from generator (G) thru resistance (B) and resistance (A) to (X), where the parallel paths are provided, one from (X) thru brush arm 25 (BR), segment (S), contact (O) and resistance (L) to the earth; the other from point (X) to the midpoint of transformer (T), where it divides between the line and the artificial line. It will be seen that, in this 30 position of (K), the path from (X) to earth thru (L) serves as voltage divider and that the potential drop thru this path will be the same as the drop thru the line or thru the artificial line and, as (L) can be made 35 smaller than (B) and (A) in series, the result will be a lower potential applied to the line at (X) than was the case when (K) was closed at (C).

Any desired proportion of current passing 40 over the line may be obtained by choosing the proper values of (B), (A) and (L). In doing this, care must be taken not to choose the resistances so that the joint resistance to an incoming current from point 45 (X) to the earth will be different when (K) is closed at (C) from the joint resistance when (K) is closed at (O); otherwise the balance of the distant duplex will be changed at each change of the position of 50 (K).

To insure the same joint resistance in either position of (K) and to provide the desired drop of potential at (X), the following formulas may be used.

55

$$L = \frac{B}{N-1} + B$$

$$A = \frac{B^2}{L-B}$$

60

where A, B and L are the resistances shown in Figure 2 and N is the required proportion. As an example, the values shown in Figure 2 are for proportions of 21 to 1. 65 This method of varying the current strength is an adaptation of the Field key system generally used in quadruplex telegraph systems.

65

Referring to Figure 2, it will be seen that 70 the duplex receiver preferably involves a vacuum tube system direct current for rectifying both halves of the alternating current waves received over the line. However, any other type of suitable receiver can be employed.

75

Having thus described our invention, we claim:

A system of signalling by means of alternating currents comprising a distributor 80 means for allocating groups of half-waves in sequence for characterizing a signal element, a line and an artificial line; a transformer, a pair of vacuum tube detectors having their grids in series through the secondary of said transformer, keying means in said artificial line comprising a series of resistances for modifying the half-wave components of the groups to give a distinguishing 85 characteristic to each signal element, and an alternating current means for supplying the requisite half-wave groups to said distributor means, to maintain the normal phase relationship with respect to the alternating 90 current wave train as a whole.

85

In testimony whereof we affix our signatures.
